(57) CLAIM

The ornamental design for an antimicrobial cover for shopping cart handle, as shown and described.

DESCRIPTION

FIG. 1 is a front perspective view of antimicrobial cover for shopping cart handle made in accordance with the subject design, shown with environment;

FIG. 2 is an enlarged partial front perspective view of the antimicrobial cover for shopping cart handle;

FIG. 3 is a rear perspective view thereof;

FIG. 4 is a front view thereof;

FIG. 5 is a top plan view thereof;

FIG. 6 is a rear view thereof;

FIG. 7 is a bottom plan view thereof;

FIG. 8 is a left side view thereof; and,

FIG. 9 is a right side view thereof.

The broken lines in FIG. 1 depict environment that forms no part of the claimed design. In FIG. 2-7 the antimicrobial cover is shown with a symbolic break in its length, represented by break lines. The break lines form no part of the claimed design.

1 Claim, 6 Drawing Sheets
